SWITCH

William C. Zaag, Huntington, N. Y., assignor to
 Telephonics Corporation, Huntington, N. Y., a
 corporation of New York

Application May 15, 1951, Serial No. 226,495

1 Claim. (Cl. 200—16)

1 This invention relates to switches, and has particular reference to the push button type of switch used in telephonic equipment, although the invention is not limited to that use.

In military field communication, it is desirable that at least part of the equipment, particularly the microphone, be disconnected except during use, and it has accordingly become the practice to provide a thumb or other finger switch button which may be conveniently pressed when talking, and released when listening, so that power is conserved and the transmission circuits do not remain closed when not in use. Such switches must be operative at all times, and must be generally immune to deterioration by reason of dampness, fouling or other results of rigorous usage in the field.

In a preferred embodiment of the invention, a spring-held plunger in the form of a thumb or finger button is arranged to be pressed to shift connections from one circuit to another and each circuit is a dual circuit, so that closure of the circuit even in the case of impairment of one set of contacts thereof is insured. The contacts are preferably of the wiping kind, so that they are self-cleaning and the uniform wiping pressure between them is not affected after almost innumerable actuations of the switch.

More specifically, the plunger operated by or including the thumb or finger button is slidably mounted in an insulating block and normally urged to one position by a spring initially presenting maximum resistance to downward movement and decreasing such resistance on continued movement of the plunger. The plunger carries contact plates on opposite sides of a length to bridge at one time two of three spring wiper contacts arranged parallel to the surface of the corresponding contact plates and so spaced that when the plunger is forced from one extreme position to the other, the center wiping contact and one or the other of the remaining contacts are simultaneously in engagement with the plunger contact plate. The wiper contact may be divided in two sets for controlling two or more circuits, and to that end they are duplicated on the opposite side of the switch block so that if the operation of one set becomes impaired, the circuit closing function of the other set is maintained.

It will be seen that the switch of this invention affords a very simple, compact and reliable arrangement for performing its intended functions under the most adverse conditions of field operation.

For a more complete understanding of the invention, reference may be had to the accompanying drawings, in which:

Figure 1 is an elevation of the switch of this

2 invention with a portion of the switch block and plunger broken away to show their construction;

Fig. 2 is a transverse section through the switch as seen along the line 2—2 of Fig. 1; and

Fig. 3 is a plan view of the switch with a portion thereof broken away to show the construction of the switch block.

Referring to the drawings, numeral 10 designates the switch block and numeral 11 the plunger, whose free end 12 constitutes the finger or thumb button, which projects from the apparatus at a convenient place for engagement by the thumb or finger of the operator with the remainder of the switch enclosed within the casing of the instrument in the usual manner.

As shown particularly in Fig. 3, the switch block 10 consists of a pair of plates 13 of suitable insulating material, such as a phenolic resin, cemented or otherwise secured together by a layer of cement 14 or other material for uniting the two plates 13 into the unitary block 10.

Secured to each plate 13 by a rivet 15 is a wiping contact 20 comprising a cooperating pair of opposed spring fingers 16 and 17. Wiping contact 20 is preferably formed by folding a strip of spring sheet metal upon itself with the folded end 18 thereof serving as the soldering lug for connecting wires. The free ends of the folded strip form the fingers 16 and 17 which are spaced apart a distance slightly less than the thickness of the contact plate 19 whose opposite surfaces are adapted to engage as shown in Fig. 3.

One half of the switch block 10 comprising the plate 13 is provided at one lateral edge with three contacts 20 spaced apart as shown in Fig. 1. The opposite lateral edge of plate 13 is provided with three similarly spaced wiping contacts 20' whose spring fingers 16' and 17' are adapted to resiliently engage the opposite surfaces of contact plate 21 in the same way that spring fingers 16 and 17 of wiping contacts 20 engage opposite surfaces of contact plate 19.

As shown particularly in Fig. 1, contact plates 19 and 21 are carried by a strip 22 of suitable insulating material such as a phenolic resin, which slides in a vertical groove 23 formed in the outer surface of plate 13. The free end of strip 22 extends beyond plate 13 to form the finger or thumb button 12 along with the complementary strip 22' sliding vertically in a slot 23' in the outer surface of plate 13' and riveted together by rivets 24 and 25, the latter passing through an elongated slot 26 passing through plates 13 and 13'. The strips 22 and 22' comprise plunger 11.

It will be observed from Fig. 1 that contact plates 19 and 21 are riveted to strip 22 of plunger 11 and are spaced apart so as to be electrically separate. The width of contact plates 19 and 21

in the direction of movement of the plunger 11 is such as to bridge two each of the wiping contacts 20 and 20' at any one time. Thus in the outward position of the thumb or finger button 12, switch plate 19 is simultaneously bridged by the upper and center wiping contacts 20 and when in the depressed position of thumb or finger button 12, the switch plate 19 is disengaged from the upper wiping contact 20 and bridges only the center and lower wiping contact 20 as shown in dotted lines in Fig. 1. Similarly, switch plate 21 bridges upper and center wiping contact 20' when the finger or thumb button 12 is in the upper or outer position, and when the latter is depressed to the dotted line position in Fig. 1, switch plate 21 is disengaged from the upper wiping contact 20' and bridges the center and lower wiping contacts 20'.

The opposite side of the switch of this invention is constructed identically to the side just described, switch plate 13' carrying wiping contact 20'' on one edge, which is insulated from wiping contact 20''' along the opposite edge of plate 13'. Wiping contact 20' and cooperating contact plate 19' correspond in every way with wiping contacts 20 and contact plate 19, whereas wiping contacts 20''' and cooperating contact plate 21' correspond in every way with wiping contact 20' and contact plate 21, respectively. Accordingly, the opposite faces of the switch are identical, but insulated from each other.

The normal condition of the switch is illustrated in Figs. 1 and 2, wherein the contact plates 19, 19', 21 and 21' bridge the corresponding upper and center wiping contacts 20, 20'', 20' and 20'''. The respective wiping contacts are urged to this normal position by a spring 27 which lies within the inverted U-shaped plunger 11 composed of the finger or thumb button 12 and plates 22 and 22'. Spring 27 extends to either side of plunger 11 to rest at its free ends on abutments 28 seated in suitable recesses in the switch block 10 as shown particularly in Figs. 1 and 2. Spring 27 is shaped with an outwardly-directed center hump engaging the lower surface of the thumb or finger button 12 and has concave portions at either side of the central hump.

A spring 27 so shaped has the characteristic of presenting a maximum resistance to the downward or inward movement of the thumb or finger button 12 upon initial movement thereof and decreasing such resistance on continued movement of button 12, so as to afford an initial resistance to the pressure of the thumb or finger and to restore the button 12 rapidly and positively when the pressure thereon is released. The dotted lines in Fig. 1 show the spring 27 in its flattened, tensioned position when button 12 is pressed inwardly to the limit of movement which is determined in both directions by the length of slot 26. Thus, rivet 25 engages the upper end of slot 26 to limit the outward movement of plunger 11 by spring 27 and engages the lower end of slot 26 to limit the inward movement of plunger 11.

In operation of the switch of this invention such as on a hand telephone of the so-called "walkie-talkie" type, the normal or outward position of button 12 holds the contact plates 19 and 21 in the open or listening circuit position, for example, and the depressed position of contact plates 19 and 21 closes the talking circuit, for example. The opposite contact plates 19' and 21' with the corresponding wiping contact 20'' and 20''' duplicate the aforementioned circuits

if desired, and may be used to preclude interruption of one or both of the circuits closed by contact plates 19 and 21, or vice versa.

The wiping pressure afforded by the spring fingers 16 and 17 of the wiping contacts 20 maintains good and clean contact, since the pressure thereof on corresponding switch plate 19 does not vary, and is not changed by flexing of the contact fingers 16 and 17, since the thickness of the contact plate 19 is uniform and its movement is always parallel to the contacting surfaces of the spring fingers 16 and 17. The same operating conditions obtain for the spring contact fingers of wiping contacts 20', 20'' and 20''' with respect to contact plates 21, 19' and 21', respectively.

It will be understood that the leads to the telephone and other circuits controlled by the switch of this invention will be soldered to the lugs 18 of the wiping contacts 20 and the corresponding soldering lugs of wiping contacts 20', 20'' and 20'''.

Although a preferred embodiment of the invention has been illustrated and described herein, it is to be understood that the invention is not limited thereby, but is susceptible of changes in form and detail within the scope of the appended claim.

I claim:

In a switch for telephonic apparatus and the like, the combination of an insulating block comprising a pair of mated plate sections having an elongated recess formed at one edge, abutment means at opposite ends of said recess, a row of spaced contact elements mounted on one surface of said block with their contact points lying in a common plane, a plunger mounted on said block for movement parallel to said row of contact elements, said plunger comprising a pair of spaced-apart side portions movable near the respective sides of said block and embracing said recess, and a head portion joining said side portions and overlying said recess, a contact plate mounted on said plunger and having its contact surface movable in said plane for wipingly engaging the contact points of said contact elements upon actuation of said plunger, a second row of spaced contact elements mounted on the opposite surface of said block parallel to the direction of movement of said plunger with their contact points lying in a second common plane parallel to said first plane, a second contact plate mounted on said plunger and having its contact surface movable in said second plane for wipingly engaging the contact points of said second contact elements upon actuation of said plunger, and a leaf spring interposed between said block and said plunger for restoring the same to predetermined position upon release of actuating pressure thereon, said spring being seated in said recess with its ends being adapted to engage said abutment means, said spring having a central hump portion for reacting against the head portion of said plunger and a pair of concave portions at either side of said central hump.

WILLIAM C. ZAUG.
